UNITED STATES PATENT OFFICE.

CHARLES J. FAULKNER, OF BALL GROUND, GEORGIA.

GRAPPLE.

1,312,241.

Specification of Letters Patent. Patented Aug. 5, 1919.

Application filed April 26, 1919. Serial No. 292,813.

To all whom it may concern:

Be it known that I, CHARLES J. FAULKNER, a citizen of the United States, residing at Ball Ground, in the county of Cherokee and State of Georgia, have invented certain new and useful Improvements in Grapples, of which the following is a specification, reference being had to the accompanying drawings.

10 This invention relates to certain improvements in grapples, and it is an object of the invention to provide a novel and improved device of this general character which is particularly designed and adapted for use for 15 the recovery of articles in submergence as in a well or the like.

It is also an object of the invention to provide a novel and improved device of this general character including a head having pivotally engaged therewith a plurality of inwardly directed hook or grappling members which assume a depending or working position by gravity and wherein said hook or grappling members are provided with means 25 whereby the same are caused to assume a raised position when the device is traveling downwardly through the water.

An additional object of the invention is to provide a novel and improved device of this 30 general character wherein certain of the pivotally supported members are caused to move inwardly to assure a more effective grip upon the load when the device is being raised or elevated.

35 The invention consists in the details of construction and in the combination and arrangement of the several parts of my improved grapple whereby certain important advantages are attained and the device rendered simpler, less expensive and otherwise, 40 more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view in side elevation of a 50 grapple constructed in accordance with an embodiment of my invention.

Fig. 2 is an enlarged fragmentary sectional view taken substantially on the line 2-2 of Fig. 1.

55 Fig. 3 is a transverse sectional view taken through the device as illustrated in Fig. 1.

Fig. 4 is a view in top plan of the head or frame and its coacting lugs as herein embodied, and

Fig. 5 is a fragmentary view in elevation 60 of a hook or grapple member constructed in accordance with a modified form of my invention.

As disclosed in Figs. 1 to 4 of the accompanying drawings, H denotes a head or 65 frame herein disclosed as substantially oblong in plan, but I do not wish to be understood as limiting myself to this particular configuration. Extending outwardly from the side and end members of the head or 70 frame H are the lugs 1 with which are pivotally or hingedly connected the shanks 2 of the hook or grappling members M.

Each of the lugs 1 is provided with a shank 3 extending through a side or end 75 member of the head or frame H and threaded upon said shank 3 is a holding or clamping nut 4 which engages the inner face of said side or end member. The lug 1 is of a diameter greater than the diameter of its 80 shank 3 so that the inner end portion of the lug affords a shoulder or abutment 5 which contacts with the outer face of the side or end member of the head or frame H so that the clamping action of the nut 4 is materially facilitated.

Each of the lugs 1 has its outer end portion bifurcated with the kerf 6 vertically disposed when the lug 1 is in proper connection with the head or frame 8, and the base 90 a of the kerf 6 is disposed on a predetermined downward and outward incline for coaction with the straight edge b of the pivoted end portion of the coacting shank 2. The straight edge b is positioned so that 95 when said edge b comes into contact with the inclined base a of the kerf 6, the upward swinging movement of the shank 2 is limited. This limiting of the upward movement of the shank 2 is of particular advantage as said shank is prevented from passing upwardly and beyond the vertical center which would otherwise materially affect the successful operation of my improved device.

100 As is clearly illustrated in the accompanying drawings, the pivoted end portion of each of the shanks 2 extends within the kerf 6 of a lug 1 and said shank is pivotally connected with its lug 1 through the medium of 110 a removable cotter 7 or the like. It is of particular advantage to have each of the

shanks 2 detachably engaged with the head or frame H so that the same can be readily replaced as the occasions of practice may necessitate.

5 The outer or working end portion of each of the shanks 2 is provided with an inwardly directed straight prong 8 of desired length and which prong is adapted to suitably engage the article to be lifted.

10 Each of the shanks 2 at a point inwardly of the prong 8 but in close proximity thereto is offset outwardly, as at 9, said offset portion 9 being directed on a downward and outward incline. Secured to said offset or inclined portion 9 is an end portion of a substantially flat wing or plate 10, the flat faces of the wing being substantially at right angles to the path of travel of the shank 2.

15 The lower end portion of the plate 10 terminates outwardly of the shank 2 and below the offset or inclined portion 9 so that when the device is lowered through the water, the resistance offered by said wing or plate 10 will cause the shank 2 to swing upwardly. However, when the downward movement of the device is limited, the shank 2 will substantially instantaneously drop, whereby the prong 8 thereof will properly engage the article to be recovered.

20 30 It is not essential that each of the shanks 2 be provided with a substantially straight prong as the prong or engaging member may be of any desired configuration as will best meet the requirements of use. As illustrated in Fig. 5, the engaging member 8^a constitutes an upwardly facing hook and which form is especially adapted for use when the area of operation is limited and the straight prongs cannot properly engage 35 the article desired to be withdrawn.

40 45 As herein embodied, a central shank 2 at opposite sides of the head H is provided with an upwardly disposed and inwardly directed extension 11. Engaged with the free extremities of the extensions 11 are the elongated members 12 preferably flexible which are also suitably secured to the coupling ring 14 carried by a lifting cable 15 or the like. The lifting cable 15 is of any desired 50 length and may be operated in any manner preferred and it will be obvious that when pull is imposed upon the cable 15 to lift the grapple and its load, the extensions 11 will cause the coacting shanks 10 to swing inwardly whereby a more effective engagement with the load is assured.

55 60 When it is preferred to cause all of the shanks 2 at a side of the head H to move inwardly under the influence of the pull imposed upon the cable 15, I employ the elongated rigid member or bar 16 detachably engaged through the instrumentality of the yokes 17 with said shanks 2 and as is particularly illustrated in Figs. 1 and 3 of the 65 drawings.

Suitably engaged with the corner portions of the head H are the upwardly converging elongated members or heads 18 secured at their upper extremities to the annular member or ring 19. The cable 15 is disposed through the annular member or ring 19 and interposed between said ring 19 and an abutment or stop 20 secured to the cable 15 inwardly of the annular member or ring 19 is an expandible member 21. The member 21, 70 as herein disclosed, comprises a coil spring encircling the cable 15 and through the medium of the member 15, the members or rods 18 operate to carry or support part of the load so that excessive strain will not be imposed upon the shanks 2 provided with the extensions 11.

75 From the foregoing description, it is thought to be obvious that a grapple constructed in accordance with my invention is particularly well adapted for use by reason of the convenience and facility with which it may be assembled and operated, and it will also be obvious that my invention is susceptible of some change and modification 80 without departing from the principles and spirit thereof and for this reason I do not wish to be understood as limiting myself to the precise arrangement and formation of the several parts herein shown in carrying 85 out my invention in practice except as hereinafter claimed.

I claim:

1. A grapple of the class described comprising a head, article engaging members pivotally secured to said head, and wings carried by said members, each of said wings having flat faces substantially at right angles to the path of travel of the coacting article engaging member.

2. A grapple of the class described comprising a head, article engaging members pivotally secured to said head, and wings carried by said members adjacent the working ends thereof, each of said wings having flat faces substantially at right angles to the path of travel of the coacting article engaging member.

3. A device of the class described comprising a head, elongated shanks pivotally engaged with said head and provided with inwardly directed work engaging portions, a part of each of the shanks adjacent its outer end being outwardly offset, and a wing secured to said offset portion.

4. A device of the class described comprising a head, elongated shanks pivotally engaged with said head and provided with inwardly directed work engaging portions, a part of each of the shanks adjacent its outer end being outwardly offset, and a wing secured to said offset portion, said wing extending outwardly of said offset portion.

5. A grapple of the class described com-

prising a head, article engaging members pivotally secured to said head, means for causing said engaging members to swing in unison, a lifting member engaged with said 5 means, a member through which the lifting member is loosely directed, connections between said last named member and the head, an abutment carried by the lifting member inwardly of the member through which said 10 lifting member is directed, and an expansi-

ble member interposed between said abutment and the member through which the lifting member is directed.

In testimony whereof I hereunto affix my signature in the presence of two witnesses. 15

CHARLES J. FAULKNER.
